UNITED STATES PATENT OFFICE.

ABRAHAM T. McCURRY, OF GOODLAND, INDIANA.

COMBINATION FOLDING BED.

SPECIFICATION forming part of Letters Patent No. 334,880, dated January 26, 1886.

Application filed May 20, 1885. Serial No. 166,198. (Model.)

To all whom it may concern:

Be it known that I, ABRAHAM T. McCURRY, of Goodland, in the county of Newton and State of Indiana, have invented a new and Improved Combined Folding Bed, of which the following is a full, clear, and exact description.

The invention consists of the construction, arrangement, and combination of parts, all as hereinafter described and claimed.

Reference is to be had to the accompanying drawings, forming part of this specification, in which similar letters of reference indicate corresponding parts in all the figures.

Figure 1 is a front elevation of a book-case with folding bed applied thereto. Fig. 2 is a rear elevation of the same, showing the bed folded; and Fig. 3 is a sectional elevation, showing the bed lowered, ready to receive the mattress and bedclothing.

20 A represents an upright article of furniture—in this instance a book-case formed in front with compartments B for books, &c., and at the top with the compartment C for bedclothing.

25 To the back of the book-case A is attached the folding bedstead D, adapted to be folded up against the back board, E, between the side boards, F F, of the case A. The bedstead D is attached by plates *a a* to the corner irons, *b b*, secured in the case A, which irons constitute two of the legs of the bedstead when it is lowered to horizontal position for use.

30 The bedstead is composed of the side pieces, *c c*, head and foot boards, *d e*, and cross-pieces *f g*, to which the wire bottom *h* is secured. *i i* represent the other two legs of the bedstead. These are hinged to the cross-piece *g*, and are braced to the side pieces, *c c*, by the folding

35 lock-braces *j j*. The bedstead is braced by a long crossed brace, G, which reaches from the cross-piece *g* to the bottom board, A', of the case A, and springs H H are attached to the bottom A' and applied to the brace G to assist in raising the bedstead D to vertical position.

40 The brace G is attached to the bottom A' in front of the irons *a a*, on which the bedstead turns, so that the outer end of the brace swings in a circle of greater radius than the foot of the

45 bedstead D. This necessitates the formation

of the slots *l l*, to receive the irons *b*, and it causes the bedstead to have an inward and downward movement in closing, and the reverse, or an upward and outward movement, in opening, so that the head of the bedstead 55 when opened to horizontal position is carried almost entirely out of the case A, so that the head of the occupant of the bed will not be enclosed by the side pieces, F F, of the case A. Another advantage of this is that a comparatively-short case, A, may be used with a long bedstead, D, or a bedstead of the usual length.

For holding the pillows and pillow-covers in place when the bedstead is closed, I hinge to the head-board *d* the board or frame J, 65 which rests against the back board, E, of the case A, so that when the bedstead is closed the pillows and pillow-covers are closed against the frame J and held from slipping down, and when the bedstead is opened the pillows and 70 covers come in proper position of their own accord upon the bed without extra attention.

When the bedstead D is folded against the back of the case A, the case may be set back against the wall, the same as any book-case, 75 wardrobe, or cabinet, and when the bed is to be used the case A has simply to be swung at one side out from the wall, to stand at right angles thereto, which can be easily done. Then the bedstead may be lowered to horizontal position 80 for use. There is a brace, *j*, for each leg *i*, and each brace is composed of two parts, *j' j''*, the latter pivoted to leg *i*, the former to side piece, *c*, of the bedstead at *j''*, and it is extended above pivot *j''* to form a short arm, *j'*. To the upper 85 end of each of these short arms is attached a rod, *j''*. These rods *j''* reach to the corner irons, *b*, to which they are attached by the long loops *j''*, so that as the bedstead is lowered and carried outward by the brace G the rods *j''* will draw backward on the arms *j'* and force the legs *i* open to proper position for supporting the bed. When the bedstead is raised to a closed position, the rods *j''*, owing to loops *j''*, will not interfere with the legs *i* 95 folding, as shown in Fig. 2, of their own weight. In this manner the legs *i* are automatic in opening and closing, and require no extra or special attention.

I am aware that folding beds have hereto- 10

fore been provided with a lever or rod pivotally connected to the head and foot portions of the bed, and adapted to open and close the foot-board and its feet upon lowering or raising the body portion of the bed, and I do not claim such as of my invention.

Having thus described my invention, what I claim as new, and desire to secure by Letters Patent, is—

- 10 1. The combination, with the casing, of a folding bedstead pivoted in slotted bearings at its head portion to said casing, and the brace hinged to the casing beyond the pivotal point of the bedstead, and connected to the bedstead 15 in front of the pivots, or toward its foot portion, whereby when the bedstead is swung down the brace will force it outward or forward, thereby rendering an outward pull by hand unnecessary, substantially as set forth.
- 20 2. The combination, with the casing having pivots or bearings, of a folding bedstead having slots in its sides, within which the pivots or bearings pass, feet hinged to the foot of the bed, and a rod or lever pivotally connected 25 to the hinged feet at its forward end, and having an elongated bearing at its rear end to receive the pivots or bearings on which the bedstead works, as set forth.
- 30 3. The combination, with the casing and the bedstead having a sliding connection therewith at its head portion, of a brace pivotally connected with the casing beyond the pivots of the head portion, and pivotally connected

to the bedstead in front of its head portion, whereby when the bedstead is lowered the brace will cause it to automatically slide outward from the casing, substantially as set forth.

4. The folding bedstead herein described, the same consisting of the casing, pivots or bearings in the lower ends thereof, the bedstead 40 having the side pieces at the head, ends slotted to receive said pivots, the folding legs at the foot portion, the rod or lever pivotally connected to the said legs at its front end, and looped at its rear end to receive the said pivots or bearings, and the brace hinged to the casing beyond the pivotal point of the bedstead and connected to the bedstead in front of the pivots, or toward its foot portion, whereby when the bedstead is swung down the brace 45 will force the bedstead forward and cause the rod to throw the legs outward, substantially as set forth.

5. The combination, with an upright article of furniture provided with a suitable recess in its back, of a bedstead hinged at its head in said recess, and of a brace of greater length than said bedstead, hinged to the foot of the bedstead and to the base of said article of furniture, substantially as shown and described.

Correction in Letters Patent No. 334,880.

It is hereby certified that in Letters Patent No. 334,880, granted January, 26, 1886, upon the application of Abraham T. McCurry, of Goodland, Indiana, for an improvement in a "Combination Folding-Bed," an error appears in the printed specification requiring correction as follows: In line 41, page 2, the comma after the word "head" should be stricken out; and that the said Letters Patent should be read with this correction therein that the same may conform to the record of the case in the Patent Office.

Signed, countersigned, and sealed this 2d day of February, A. D. 1886.
